UNITED STATES PATENT OFFICE.

WILLIAM N. OEHM, OF MICHIGAN CITY, INDIANA.

DRAFT-ARM.

1,353,488.

Specification of Letters Patent. Patented Sept. 21, 1920.

Application filed August 12, 1919. Serial No. 317,003.

To all whom it may concern:

Be it known that I, WILLIAM N. OEHM, a citizen of the United States, and resident of Michigan City, county of Laporte, and State 5 of Indiana, have invented certain new and useful Improvements in Draft-Arms, of which the following is a specification, and which are illustrated in the accompanying drawings, forming a part thereof.

10 The invention relates to draft arms, and has for its object the production of a draft arm which shall be stronger for the amount of metal utilized than draft arms now in use. A further object of the invention is the 15 provision of draft arms which will allow of a more secure attachment to the center sills than has been heretofore obtained.

In the accompanying drawings,

Figure 1 is a side view of the draft arm 20 showing the bolster and end sill in section;

Fig. 2 is a plan view of a pair of draft arms and a portion of the bolster, with parts broken away to show the draft arm in section;

25 Figs. 3 and 4 are sections on lines 3—3 and 4—4, respectively, of Fig. 1.

In the drawings 10 is used to designate the wrought draft arm as a whole, which draft arm comprises a web 11 and flanges 12.

30 The center sills of the car preferably take the form of channel beams 13, having webs 14 and flanges 15. The bolster is indicated at 16, and the lower bolster plate at 17. The opening for the king pin is seen at 18, resulting from semi-cylindrical depressions in 35 the mating filler blocks 19.

I have illustrated my draft arms as nest-
ing with the channels which constitute the

center sills of the car, and as having the webs of said sills riveted to the draft arms, 40 as shown at 20. The end sill of the car is indicated at 21, and draft and buffing lugs at 22, 23.

It will be observed from the disclosure of Fig. 2 and a comparison of Figs. 3 and 4, 45 that the metal of the web of the channel, comprising the draft arm, is thicker at its point of attachment to the center sills than it is toward the end. This increased thickness results in a more secure attachment of 50 the rivets 20, or equivalent securing means, and also places the metal of the draft arm where the greatest stresses are expected to occur, thereby utilizing the metal to the best effect. 55

I have described and illustrated a preferred form of my invention, but it will be understood that various modifications may be made therein without departing from the spirit thereof. Therefore I do not desire to 60 be limited except by the scope of the allowed claim.

I claim as my invention:

In a railway car, in combination, a center sill projecting beyond the bolster, bolster 65 filler blocks between said sills and bolster members having side and end flanges exterior of said sills, a draft arm nesting with the projecting end of the sill and abutting against one of said members, a buffing block 70 interior of said projecting end and abutting against one of said filler blocks, and rivets securing said sill, draft arm and buffing blocks together, the web of the draft arm being thickened at its area of attachment. 75

WILLIAM N. OEHM.
